UNITED STATES PATENT OFFICE

HERMAN FORTKAMP, OF CHICKASAW, OHIO

CHANGEABLE SIGN

Application filed April 25, 1929. Serial No. 358,062.

The present invention is directed to improvements in changeable signs.

The primary object of the invention is to provide a device of this character which can be conveniently applied to a gate or fence post or to any other suitable support along the side of a roadway, the construction being such that the sign can be adjusted to indicate that a certain class of stock or commodity is 10 for sale.

Another object of the invention is to provide a sign of this character which can be easily and quickly adjusted and positively held in its adjusted position.

Another object of the invention is to provide a device of this character so constructed that it will not be affected by the weather.

Another object of the invention is to provide a device of this character which is 20 exceedingly simple in construction, durable, efficient in operation, and one which can be manufactured at a very small cost.

With these and other objects in view, this invention resides in the novel features of 25 construction, formation, combination and arrangement of parts to be hereinafter more fully described, claimed and illustrated in the accompanying drawing, in which:

Figure 1 is a front view of the device.

Figure 2 is a sectional view on the line 30 2-2 of Figure 1.

Referring to the drawing, 1 designates a bracket having a horizontal flange 2 formed upon its lower end which serves to secure the 35 bracket to a post 3 or any other suitable support.

The bracket is provided intermediate its ends with an opening 4 in which is engaged the inner end of a bolt 5, said bolt having a 40 sleeve 6 engaged thereon which has its rear end impinged against the bracket 1, thus forming a spindle the purpose of which will be later explained.

A dial 7 is provided and has a hub 8 carried thereby which is adapted to rotatably engage the sleeve 6, said dial being provided with a peripheral horizontal flange 9, said flange having formed in its outer face a plurality of notches 10, equally spaced for 50 selective engagement with the pin 11.

Riveted to the bracket 1 is a frame 12 which includes vertically spaced arms 13, said arms having perforations 14 therein for slidably supporting the pin 11, said pin being provided with a stop 15 for engaging the upper 55 end of the coil spring 16, the lower end of which rests upon the lower arm 13 of the frame. Obviously, this spring will normally hold the pin yieldably engaged in a selected notch.

The front face of the dial 7 has marked thereon in any suitable manner, radial lines 17 which divide the dial face into spaces 18, and in these spaces are designated the character of goods for sale. As shown, the dial 65 is marked with various classes of farm stock but it will, of course, be understood that commodities such as hay, vegetables and the like can be also displayed upon the dial. The sleeve 6 obviously serves as a spindle for the 70 hub 8.

Fixed to the forward end of the bolt 5 is a pointer 19, said pointer being horizontally disposed and is held tightly engaged with the adjacent end of the sleeve 6 in order that 75 the sleeve will prevent the hub 8 from contacting with the pointer but, at the same time, permitting the dial to be freely rotated when desired. Obviously, the nut 20 upon the bolt will hold the pointer in its proper position.

To exclude moisture and dust from the dial, a lens 21 is secured to the flange 9 by a ring 22, or in any other suitable manner.

Fixed to the upper end of the bracket 1 is a plate 23 which carries a clamping bolt 24, 85 said bolt being engaged in the slot 25 formed in the extension 26 carried by the indicator plate 27, said plate having marked thereon in any approved manner, the words For Sale. Obviously, this plate can be secured 90 in the position shown in full lines in Figure 2, to indicate to passersby that some article of certain character is for sale, this being, of course, indicated by the pointer 19, as shown in Figure 1. When the plate 27 is in the 95 position shown in dotted lines in Figure 2, it will, of course, be indicated that no articles are for sale.

It will be obvious that when it is desired to change the sign, that it is only necessary 100

to pull the pin 11 downwardly and rotate the dial so that the pointer will coincide with another designation, after which the pin is released and the spring 16 will hold the same engaged in a selected notch, thereby holding the dial against accidental rotation.

From the foregoing, it is thought that the construction, operation and many advantages of the herein described invention will be apparent to those skilled in the art, without further description, and it will be understood that various changes in the size, shape, material, proportion and minor details of construction may be resorted to without departing from the spirit or sacrificing any of the advantages of the invention.

What I claim is:

1. In a sign, the combination with a bracket having a bolt fixed thereto, of a pointer fixed to the bolt, a dial rotatably supported by the bolt and having indicia thereon for cooperation with the pointer, said dial having a marginal flange provided with notches, a spring pressed pin carried by the bracket for selective engagement with the notches.
2. In a sign, the combination with a bracket, of a dial rotatably supported thereby, a pointer cooperatively associated with the dial, means carried by the bracket for holding the dial in various positions of rotative adjustment, and a sign plate adjustably connected with the bracket.
3. In a sign, the combination with a bracket having a bolt carried thereby, of a sleeve engaged on the bolt and having one end bearing against the bracket, a pointer engaged with the bolt and bearing against the other end of the sleeve, adjustment of the bolt serving to prevent rotation of the sleeve and pointer, a dial having a hub rotatably engaged on the sleeve and having indicia thereon for cooperation with the pointer, and means carried by the bracket for engagement with the dial to hold the same in adjusted position.

In testimony whereof I affix my signature.

HERMAN FORTKAMP. [L. S.]
